UNITED STATES PATENT OFFICE.

MAURICE A. MICHAELS, OF MERIDEN, CONNECTICUT, ASSIGNOR TO JULES PANIGOT,
OF MERIDEN, CONNECTICUT.

BALL CASTER.

Application filed September 10, 1920. Serial No. 409,424.

To all whom it may concern:

Be it known that I, MAURICE A. MICHAELS, a citizen of the United States of America, residing at Meriden, New Haven County, 5 Connecticut, have invented a new and useful Ball Caster, of which the following is a specification.

My invention relates to a ball caster.

It is the principal object of my invention 10 to provide a very simple and efficient caster.

It is a further object to provide a caster which can be made of stamped-out parts for cheapening the construction.

Other objects and advantages will appear 15 as the specification proceeds.

My invention in its preferred form comprises a sheet metal housing having one or more apertures therein, through which one or more balls partially extend. A plate, 20 preferably of hardened metal, holds the balls in place in the housing and provides a bearing surface for the balls. The plate is held in place by bent edges of the housing which may also serve to secure the caster to 25 a support, such as the leg of an article of furniture.

In the drawings, which show merely preferred forms of my invention:—

Figure 1 is a sectional view of an assembled 30 caster, taken substantially in the plane of the line 1—1 of Fig. 2.

Fig. 2 is a bottom plan view of an assembled caster;

Fig. 3 is a top plan view of an assembled 35 caster;

Fig. 4 is a view of the blank from which my caster housing is formed;

Fig. 5 is a view similar to Fig. 1, showing a modified form; and

Fig. 6 is a view of the usual caster pintle 40 having means for securing my improved caster thereto.

In said drawings, 1 indicates a blank from which the housing is made. This blank may 45 be of any suitable material, preferably of sheet metal, which may be easily stamped. The blank is provided with one or more ears 2, and these ears are preferably sharpened on the ends, as indicated at 3. The 50 metal of the blank proper is preferably cut in adjacent the ears a distance equal to the thickness of the metal, as indicated at 4, for a purpose to be afterward described. One or more apertures, such as 5, are formed in 55 the blank, and a slight burr, extending out-

wardly, may be left thereon, to provide a bearing surface for a ball and to hold the latter in the housing. The blank is stamped up to form a cup 6, and a shoulder 7 is preferably formed in the cup.

After one or more balls have been placed in the housing and slipped into the apertures 5, a plate 8, preferably of hardened steel, is placed in the housing and may rest on the shoulder 7. In the particular form shown the ears 2 are next bent inwardly and over the plate 8, to secure the latter in place in the housing. By having the blank or housing cut inwardly slightly, as indicated at 4, the ears are bent so that the outer surface of each ear will come substantially flush with the upper end 9 of the housing, as indicated in Figs. 1 and 5.

The points 3 of the ears are bent to project upwardly above the housing and may be driven into an article of furniture for securing the caster thereto. It is perfectly obvious that other means, such as a screw or nail 10, may be used in place of the sharpened ears for securing the caster to an article of furniture.

In the form of caster shown in Fig. 1 the plate 8 is shown as a plain, flat plate. In the modification shown in Fig. 5 I have shown a plate having a slightly spherical surface. The reason for this form of plate will now be explained. With a caster containing a plurality of balls it is improbable that all the balls will be in contact with the floor and the plate at the same time; this for the reason that most floors are comparatively irregular on the surface. With a plate such as 11, (Fig. 5) with a convex or spherically curved surface, the ball which is in contact with the plate and the floor will cause the plate to slide and tend to let the ball which is in contact with the floor recede into the housing, and this lowering of the housing will permit the other ball or balls, which were previously not in contact with the floor, to come into contact therewith. Therefore, with the plate convex or spherically curved shape, all of the balls will be in contact with the floor at the same time and each will bear its proper proportion of the load. As shown in Fig. 5, the plate 11 is loosely mounted and is held in the housing by means of the ears 2, in the same way that the plate 8 is held in Fig. 1.

It may sometimes happen that the means

described for securing the caster to a support would be incapable of use with articles of furniture in existence, which are equipped to take the usual form of pintle casters. I have therefore shown in Fig. 6 a usual form of pintle 15, adapted to enter the usual hole in the leg of an article of furniture, and on the bottom of the pintle is shown a plate 16, having a series of apertures 17 therein through which the ears 2 may be inserted and bent over, to hold my improved caster to the pintle 15. It is obvious that the method of attachment just described is merely illustrative and one of many which could be devised.

While I have described in detail specific forms of my invention, I wish it to be understood that various modifications and changes may be made, all coming within the scope of the appended claims.

I claim:

1. In a ball caster, a housing having an aperture therein, a ball in said housing and extending partially through said aperture, a bearing plate in said housing for contact with said ball, and an ear on said housing for holding said plate in place, the upper surface of said ear being substantially flush with the upper edge of said housing when the parts are assembled, a prong on said ear,

said ear and prong being supported by said plate to resist force applied in driving in said caster.

2. In a ball caster, a housing having a plurality of apertures therein, balls in said housing and extending partially through said apertures, a bearing plate in said housing and having a convex surface for contact with said balls, means for holding said plate in said housing, said plate being loosely mounted in the housing whereby when the caster is upon an uneven surface the plate may move in the housing to permit all of the balls to engage both the plate and the uneven surface.

3. In a ball caster, a housing having an aperture therein, a ball in said housing and extending partially through said aperture, a bearing plate in said housing for contact with said ball, and an ear on said housing for holding said plate in place, said ear having a sharpened end for attachment to a leg and extending a substantial distance inwardly from the edge of the housing whereby the ear may be applied to a leg of smaller diameter than the caster and the sharpened end of the ear driven into the leg a substantial distance away from the edge of the latter.

MAURICE A. MICHAELS.
